Peter Linquien's Design for Clock Case

No 946.

Patented Octo. 6. 1857.

Des. 946

Pietro Lingueiani, of West Haven, Conn:

Assignee to

W. L. Bradley, W. Hubbard & A. L. Bradley, of same place.

Letters Patent No. 946. Dated Oct: 6. 1857.

The schedule referred to in these Letters Patent, and making part of the same.

To all whom it may concern:

Be it known that I, Pietro Lingueiani, of West Haven, in the County of New Haven, and State of Connecticut, have invented or produced a new and original design for a clock case, which I term the Santa Claus, and I do hereby declare that the following is a full, clear and exact description of the same, reference being had to the annexed drawing, making a part of this specification, which drawing is a front elevation of a Clock Case, showing my design.

A, represents a circular base which supports a human figure B. — The dial C, being at the center of the front of the body. The figure has a loose sack coat, D, provided with a cap D, loose pants E, short top boots F, and a skull cap G. The hair H, is long extending down upon the shoulders, and the figure is represented as holding toys I, in either hand and under the arms and in the pockets, as plainly shown in the drawing, a trumpet (a), Military hat (b) and doll (c) being at one side of the figure, and a guitar (d) book (e) musket (f) drum (g) and rattle (h) being at the opposite side, the whole forming a representation of Santa Claus laden with toys.

DB

Des. 946

I claim the figure, its general configuration and arrangement of parts as shown and described to form a new and original design for a clock case, termed the Santa Claus.
